CLAIM

The ornamental design for a lidded food storage bowl, as shown and described.

DESCRIPTION

FIG. 1 is a top perspective view of a lidded food storage bowl showing our new design;

FIG. 2 is a left side elevation view thereof;

FIG. 3 is a front elevation view thereof; and,

FIG. 4 is a top plan view thereof.

The broken lines in the drawings depict portions of the lidded storage bowl that form no part of the claimed design.
